PUMP CYLINDER BLOCK DAMPENING MEANS
Tadeusz Budzich, Shaker Heights, Ohio, assignor to The Weatherhead Company, Cleveland, Ohio, a corporation of Ohio

Filed Mar. 9, 1961, Ser. No. 94,465
7 Claims. (Cl. 103—37)

This invention relates to variable volume pumps and more particularly to a variable volume pump of the type disclosed in my co-pending application, Serial No. 88,142, filed February 9, 1961.

Variable volume pumps having a plurality of pumping cylinders in a cylinder block which is mounted to move so as to vary the effective pumping stroke provide a number of advantages with respect to efficiency in operation, simplicity in construction and low cost to manufacture. Pumps of this type are disclosed in my co-pending application Serial No. 825,005, filed July 6, 1959.

It is among the objects of the present invention to provide a pump having an elongated housing with an end cap at one end of the housing and a cylindrical wall portion at the interior of the housing adjacent the end cap and wherein a cylinder block is mounted for axial movement in the housing and the cylinder block is provided with a circular cross-section so as to be guided within the cylindrical portion of the housing toward and away from the end cap and wherein the space between the cylinder block and the end cap forms a dash-pot chamber for dampening the axial movements of the cylinder block.

In it a further object of my invention to provide a pump according to the preceding object wherein a passageway is provided through the cylinder block to form a restricted flow path for fluid and wherein the effective cross-sectional area of such flow path may be varied so as to vary the dampening effect with respect to the cylinder block.

It is a further object of my invention to provide a pump according to the preceding objects wherein said restricted flow path is in the form of an axial groove along the outer periphery of the cylinder block and wherein a plug carried by the wall of the housing is adjustably arranged within said groove and wherein the plug is accessible from the exterior of the housing for varying the flow path.

It is a further object of this invention to provide a pump according to the preceding objects wherein the plug and groove which provide the restricted flow path also serve as a longitudinal guide for the cylinder block to prevent rotation of the cylinder block within the pump housing.

Further objects and advantages relating to accuracy in pump control, ruggedness of construction and ease of adjustment will appear from the following description and the appended drawings wherein:

FIG. 1 is a longitudinal view, partly in section, through a pump made according to my invention;

FIG. 2 is a transverse sectional view taken along the line indicated at 2—2 of FIG. 1; and

FIG. 3 is a longitudinal sectional view of the cylinder block made according to my invention.

As will be understood by reference to said co-pending applications and as shown in the drawings, a housing 6 is provided with an end cap indicated in its entirety at 7 and a cylinder block indicated at 10 is mounted within the housing 6 for axial movement toward and away from the end cap 7. The interior of the housing 6 is provided with a forwardly disposed cylindrical wall portion 8 terminating in a shoulder 9 which serves as an abutment for a shoulder 11 on the end cap 7. The in-

terior of the housing is normally filled with fluid to be pumped through a suitable inlet (not shown).

A second cylindrical wall portion at the interior of the housing is indicated at 12 and the cylinder block 10 is provided with a rearward portion 13 which is circular in cross-section and fits snugly along the cylindrical wall 12. The cylinder block 10 includes a cylindrical portion 14 at the forward end thereof which fits snugly along the cylindrical surface 8 at the interior of the housing. The space on each side of the cylinder block 10 is filled with fluid at pump inlet pressure. Intermediate the wall portions 8 and 12 of the housing a re-entrant channel 15 is formed to provide a volume of fluid to be pumped adjacent the outer port 16 for the pumping cylinder 17. It will be understood that a plurality of pumping cylinders are arranged about the cylinder block identical with cylinder 17. A supporting plate 18 is secured to the housing and serves as a stop or abutment for the end face 19 of the cylinder block 10 as the block 10 is retracted from the end cap 7.

A spring 20 is arranged between the end cap 7 and the cylinder block 10 so as to normally bias the cylinder block into the retracted position in abutment with the supporting plate 18. Inner ports 21 are provided for the pumping cylinder 17 and a chamber 22 adjacent the inner ports 21 communicates with a bore 23 in supporting plate 18 so as to permit fluid flow from the interior of the housing to the inner port 21 of the pumping cylinder. The inner port 21 and the outer port 16 are formed by inner and outer annular grooves 21a and 16a, respectively. Each pumping cylinder 17 is provided with a reaction piston 24 which is arranged in sealing contact as at 25 with a tubular port member 26. The end cap 7 is provided with a bore 27 in alignment with each of the pumping cylinders 17. This bore is threaded as at 28 to receive a plug 29 serving to hold a check valve cage 30 in abutting contact with the tubular port member 26.

A check valve plate 31 is biased to closed position by spring 32 carried within the cage 30. The walls of the cage 30 are apertured as at 33 so that as fluid under pressure from the pumping cylinder 17 unseats the check valve plate 31 such fluid is conducted through the apertures 33 into the connecting passage 35 and thence into the outlet chamber 36.

A spring plate 37 serves as an abutment for one end of a spring 38 surrounding the reaction pistons 24. A snap-ring 39 and spring abutment ring 40 carried by the reaction piston 24 serve as the abutment at the other end of the spring 38. Accordingly it will be understood that each of the reaction pistons is normally biased by its spring 38 into sealing engagement with the end face of the port member 26. It will also be understood that fluid pressure in the cylinder is effective across the wall area of the reaction piston 24 to maintain a pressure seal at 25.

Reciprocating pistons 45 having piston rods 46 are arranged to be advanced by cam means or the like into the pumping cylinders 17. Springs 47 are arranged to retract the pistons 45 from the pumping cylinders 17. The stroke of the reciprocating pistons 45 is fixed accordingly to the output volume of the pump and may be varied by reason of the cut-off position of the forward end face 45a of the piston 45 with respect to the ports 16 and 21. Preferably the parts are proportioned with respect to the piston stroke so that when the cylinder block 10 is at its maximum forward position, the piston on the forward limit of its stroke does not close off the ports 16 and 21 and accordingly the pump will be at a zero output position.

The movement of the cylinder block 10 is preferably determined by control means indicated in its entirety as at 50 and as disclosed in detail in my said co-pending

application Serial No. 88,142, filed February 9, 1961. The control assembly 50 moves toward and away from the end cap 7 with the cylinder block 10 by reason of the shoulder 51 and the snap-ring 52 which holds the control assembly in the central opening 53 of the cylinder block 10. A transfer tube 54 is mounted to extend into the outlet chamber 36 and accordingly fluid at outlet chamber pressure is conducted into the control assembly 50 where such fluid pressure is effective to determine the position of the cylinder block 10.

It will be understood that the pump housing 6 is filled with fluid to be pumped out through the outlet chamber 36. The housing is divided generally into a forward chamber as at 60 in front of the cylinder block 10 and a rearward chamber as at 70 behind the cylinder block. The fluid on both sides of the cylinder block 10 is at a low or inlet pressure and is adapted to be carried into the inlet ports 16 and 21 of the pumping cylinders. The only fluid connection or flow passage between the forward chamber 60 and the rearward chamber 70 is provided by a rectangular groove 61 extending axially along the periphery of the forward cylindrical portion 14 of the cylinder block 10. Since movement of the cylinder block 10 under the action of control means 50 will require fluid to flow between the chambers 60 and 70 through axial groove 61, the amount of restriction provided by the grooves determines the rate of fluid transfer between the chambers 60 and 70 and hence the speed of response of the cylinder block.

The housing 6 is provided with a radial bore 62 threaded at 63 to receive a plug 64 arranged to project radially into the groove 61 in the cylinder block 10. Plug 64 has a diameter equal to the width of groove 61, so that the only flow passage between the chambers 60 and 70 is provided by the space 67 between the end of plug 64 and the bottom of groove 61. The plug 64 is provided with a socket head 65 and with an O-ring seal as at 66. Accordingly, it will be understood that by turning the plug 64 on its threaded connection 63, the plug may be advanced or retracted with respect to the groove 61 to vary the effective area of the flow passage 67. Thus, the dampening of the axial movement of the cylinder block 10 is conveniently controlled exteriorly of the pump housing. The plug 64 also functions to guide axial movement of the cylinder block and position it radially within the pump housing 6 so that each of the pumping cylinders 17 and reaction pistons 24 is maintained in alignment with its associated port member 26 carried in the end cap 7.

As described in considerable detail in my co-pending application Serial No. 88,142, filed February 9, 1961, the control mechanism 50 includes a pilot valve member 55 which is moved axially relative to the bore 56 to admit fluid from the outlet chamber 36 through transfer tube 54 and into a control chamber 57 and to conduct fluid from the control chamber 57 into the interior of the pump housing into space 70. The parts are constructed and arranged so that when a predetermined high pressure, such as, for example, 2000 pounds per square inch, occurs in the outlet chamber 36, fluid at such pressure is directed into the control chamber 57 and, by reaction with a surrounding cylinder 58, the cylinder block 10 is moved toward its position of minimum output. In the event the fluid pressure in the outlet chamber 36 should drop below such predetermined figure of 2000 pounds per square inch, fluid pressure will be discharged from the control chamber 57 and the cylinder block 10 will be moved towards its position of maximum displacement by spring 20.

It will be understood by those skilled in the art that the cylinder block should not be susceptible to hunting or oscillations in response to fluctuations in fluid pressure at the outlet. The restricted flow path 67 provided by the groove 61 and the plug 64 guards against hunting

and sudden changes in position of the cylinder block 10. For example, even though the control means 50 should respond to a sudden pressure increase in the outlet chamber 36, the movement of the cylinder block 10 will be damped by the restriction encountered in the flow passage at 67 as the fluid in forward chamber 60 is moved out of chamber 60 into rearward chamber 70. A similar dampening effect occurs on a sudden drop in fluid pressure at the outlet chamber 36. The spring bias provided by the spring 20 would normally move the cylinder block 10 quickly toward its position of maximum displacement. Said rapid movement, however, is damped by fluid flow from the rearward chamber 70 through the restricted flow passage 67 into the forward chamber 60.

Although I have shown and described my invention in considerable detail, it will be appreciated by those skilled in the art that numerous variations may be made therein without departing from the scope of the invention as defined in the following claims.

What is claimed is:

1. A pump comprising a housing, said housing having an end cap at one end thereof provided with an outlet chamber, said housing having a cylindrical wall portion at the interior thereof adjacent said end cap, a cylinder block mounted for axial movement in said housing, said cylinder block having a peripheral surface providing cylindrical portions conforming to the cylindrical contour at the interior of the housing adjacent the outlet, said cylinder block being guided for axial movement within said housing by sliding movement along said cylindrical surfaces, said housing having a fluid inlet to fill said housing with fluid to be pumped, said fluid within the housing being at inlet pressure, said cylinder block having a passageway therethrough connecting that space in the housing between the end cap and the cylinder block to that space in the housing at the other side of the cylinder block whereby movement of the cylinder block is damped by the fluid flow through said passageway, and adjusting means to vary the area of said passageway to vary the dampening effect.

2. A pump comprising a housing, said housing having an end cap at one end thereof provided with an outlet chamber, said housing having a cylindrical wall portion at the interior thereof adjacent said end cap, a cylinder block mounted for axial movement in said housing, said cylinder block having a peripheral surface providing cylindrical portions conforming to the cylindrical contour at the interior of the housing adjacent the outlet, said cylinder block being guided for axial movement within said housing by sliding movement along said cylindrical surfaces, said housing having a fluid inlet to fill said housing with fluid to be pumped, said fluid within the housing being at inlet pressure, said cylinder block having an axial groove along its periphery to provide a path therethrough connecting that space in the housing between the end cap and the cylinder block to that space in the housing at the other side of the cylinder block whereby movement of the cylinder block is damped by the fluid flow through said passageway, said housing having an adjustable member in the wall thereof extending into said groove to adjust the size of the fluid flow path therealong.

3. A pump comprising a pump housing, a cylinder block slidably mounted within said housing for axial movement therein, said cylinder block providing a seal dividing the interior of said housing into first and second chambers, an outlet on said pump housing, an inlet to the interior of said pump housing opening into one of said chambers, a plurality of axially aligned cylinder bores in said cylinder block, a piston in each of said cylinder bores, means to reciprocate said pistons in said cylinder bores, port means to admit fluid into said cylinder bores, means connecting each of said cylinder bores to said outlet, a restricted passage in said cylinder block

interconnecting said first and second chambers, and adjusting means to vary the area of said restricted passage.

4. A pump comprising a pump housing, a cylinder block slidably mounted within said pump housing for axial movement therein, said cylinder block being formed to provide a seal dividing the interior of said housing into first and second chambers, an outlet on said pump housing, an inlet to the interior of said pump housing opening into one of said chambers, a plurality of axially aligned cylinder bores in said cylinder block, a piston within each of said cylinder bores, means to reciprocate said pistons in said cylinder bores, port means to admit fluid into said cylinder bores, means connecting each of said cylinder bores to said outlet, an axial groove extending along the outer periphery of said cylinder block adjacent said pump housing and interconnecting said first and second chambers, and adjusting means to vary the cross-sectional area of said axial groove.

5. A pump comprising a pump housing, a cylinder block slidably mounted within said housing for axial movement therein, said cylinder block being formed to provide a seal dividing the interior of said housing into first and second chambers, an outlet on said pump housing, an inlet to the interior of said pump housing opening into one of said chambers, a plurality of axially aligned cylinder bores in said cylinder block, a piston in each of said cylinder bores, means to reciprocate said pistons in said cylinder bores, port means to admit fluid into said cylinder bores, means connecting each of said cylinder bores to said outlet, an axial groove on the outer periphery of said cylinder block interconnecting said first and second chambers, and a guide pin mounted on said pump housing to project into said axial groove and adapted to prevent relative rotation between said cylinder block and said pump housing, said guide pin reducing the effective passage area of said axial groove to restrict fluid flow between said first and second chambers.

6. A pump comprising a pump housing, a cylinder block slidably mounted within said housing for axial movement therein, said cylinder block providing a seal dividing the interior of said housing into first and second chambers, an outlet on said pump housing, an inlet to the interior of said pump housing opening into one of said

chambers, a plurality of axially aligned cylinder bores in said cylinder block, a piston in each of said cylinder bores, eccentric cam means to reciprocate said pistons in said cylinder bores, port means to admit fluid into said cylinder bores, means connecting each of said cylinder bores to said outlet, an axial groove on the outer periphery of said cylinder block interconnecting said first and second chambers, a guide pin adjustably secured to said pump housing to project into said axial groove and prevent relative rotation between said cylinder block and said pump housing and to reduce the effective passage area of said axial groove, whereby adjustment of said guide pin within said pump housing varies the effective area of said axial groove.

15 7. A pump comprising a pump housing, a cylinder block slidably mounted within said pump housing for axial movement therein, said cylinder block providing a seal dividing the interior of said housing into first and second chambers, an outlet at one end of said pump housing, an inlet to the interior of said pump housing opening into one of said chambers, a plurality of axially aligned cylinder bores in said cylinder block, a piston within each of said cylinder bores, eccentric cam means to reciprocate said pistons in said cylinder bores, port means in said cylinder block to admit fluid into said cylinder bores, means connecting each of said cylinder bores to said outlet, an axial groove on the outer periphery of said cylinder block adjacent said pump housing to interconnect said first and second chambers, a plug threadedly engaged in said pump housing and extending radially into said axial groove to reduce the effective passage area of said groove, whereby the depth of engagement of said plug in said axial groove is adjustable by threaded rotation of said plug in said pump housing.
